UNITED STATES PATENT OFFICE.

TERENCE CLARK, OF PITTSBURG, PENNSYLVANIA.

MANUFACTURE OF PLATE AND WINDOW GLASS.

Specification of Letters Patent No. 8,994, dated June 8, 1852.

To all whom it may concern:

Be it known that I, TERENCE CLARK, of the city of Pittsburg, county of Allegheny, and Commonwealth of Pennsylvania, have 5 invented a new and Improved Mode of Manufacturing Plate and Window Glass; and I do hereby declare that the following is a full and exact description thereof, reference being had to the annexed drawings, 10 forming part of this specification, wherein—

Figure 1 is a perspective view of my machine for rolling glass; Fig. 2 is a longitudinal vertical section of my rolling machine; Fig. 3 is a representation of the truck 15 for receiving the plate glass as it leaves the rolls; Fig. 4 is an inverted view of the truck showing the rack work underneath; Fig. 5 is an inverted view of the truck, with part 20 of the bottom removed to show how it is packed between the ribs and braces with clay; Fig. 6 is a representation of the internal arrangement of ribs and braces in the truck; Fig. 7 is a view of the fork used for turning the plate glass; Fig. 8 is a perspective 25 view of the fire polishing oven; Fig. 9 is a horizontal section of the oven through the openings A A showing the truck in place and Fig. 10 is a transverse vertical section of the oven through the openings A A showing 30 the truck in place.

All the similar parts in the several figures are marked with the same letters for convenience of reference.

My invention consists first in a new and 35 improved combination of machinery for rolling plate glass, and secondly for a new and improved construction of an oven for fire polishing the plates or sheets of glass.

My machine for rolling the glass is represented in perspective in Fig. 1.

A frame work, a, a , made of iron or wood, supports the heavy chilled iron rollers, b, b' which lie horizontally across the machine and parallel to each other; each roller carries 45 at one end a cog-wheel, r, r' , with long teeth, so arranged that the pitch line of the teeth is outside of the circumference of the rollers in order that these two cog-wheels may gear into each other when the circumferences of the rollers are about $\frac{1}{16}$ of an inch apart and so as to admit of the rollers being separated about one inch apart without being put out of gear. These rollers, being hollow, have end pieces c, c' secured 50 into them which are perforated with four or five holes large enough to insert char-

coal for heating the rollers. The journals, d, d' , on which the rollers turn, at both ends of the rollers are hollow, to permit the smoke to escape and the charcoal to burn. The journal blocks, e, e' support the rollers. The distance between the roller, b , and the roller, b' , may be varied by means of the set screws s which turn in the brackets f , and work against the journal blocks, e, e' , 60 pushing them nearer to, or drawing them farther from, the journal blocks, e , as may be required. The arrangement of brackets and screws is the same at each end of the roller, b' , one end being concealed in the perspective view. Motion is given to the rollers by means of a pinion, p , which gears into the cog-wheel, r , on the roller, b , working on an axis, g , which is supported by uprights, h, h' , which form part of the journal blocks, e, e' . This axis is turned by hand with a crank, k , or by steam power communicated to the axis g in any ordinary manner. Two parallel grooves are cut around the circumference of each roll, (o, o, o', o'), 65 at the required distance apart for the sheet of glass to be rolled. These grooves receive two strips of metal, i, i' , which regulate the width of the glass which is poured between the rollers. The melted glass is poured between the rollers from a ladle or pot, and the rollers turning both inward, the glass is rolled of the width fixed by the strips, i, i' , and the same thickness as the distance 70 that the rollers are set apart. If the glass 75 is rolled is window glass of the common thickness, say $\frac{1}{16}$ of an inch thick, or less, it will rapidly as to hang down without stretching so much as to impair its quality or vary its thickness; but as this is not the case with 80 plate glass, it must not be allowed to hang down after it passes from the rollers, but is received on a truck which passes under the rollers, as hereinafter described.

When plate glass is to be rolled, the rollers b, b' , are placed the necessary distance apart by turning the set screws marked, s . A railway truck, see Fig. 3, (the construction of which is hereinafter more particularly described) is placed on the track A A under the frame work entering at the end nearest to the eye in Fig. 1, the rack work G under the truck gearing into the pinion P. This pinion is on an axis, C, and is carried by the supporters, B, B. At the end of the axis, C, and outside the frame 85 90 95 100 105 110

work is a pulley or drum D which connects by a band or rope *t* with the large drum, E, which is on an extension of the axis of the roller, *b*, with which it turns, thus communicating motion to the pinion P, which, gearing into the rack work of the truck T impels it slowly forward. The size of the drums and pinions are so regulated to correspond with the quantity of glass turned out by the rollers, that the truck T passes forward just fast enough to receive and carry off the sheet of plate glass as it passes from the rollers. The rail road track A A on which the truck or trucks rest extends from the rolling machine to the oven Fig. 8, so that when the truck has received the sheet of plate glass, it is pushed forward into the oven, or if the oven is large enough to receive more than one truck, two or more may be attached together, and all carrying the glass deposited on them by the rolling machine pushed forward to the oven.

The cars or trucks on which the glass lies as it passes from the rollers are made of iron as represented in Figs. 3 and 4. The upper surface is highly polished, so as not to impair the surface of the glass. These cars may be connected together by catches, F, F, or in any ordinary method, the rack work, G, underneath being so made as to gear with the pinion, P. The trucks used are braced internally by cross pieces V V and ribs *v v* and the spaces between the ribs and braces are packed with clay *x* to prevent the truck from becoming too hot and warping. See Fig. 5.

Fig. 8 represents a perspective view of the oven, one front only being shown, as the two fronts are alike. It is built of brick and consists of two long narrow chambers, arched over the top. Between these chambers is a narrow space, L, extending the whole length and forming a flue for the flame and smoke. From the center of this space or flue rises the chimney, M. The only communication between this flue and the chambers is by means of small openings, Q, Q, Q, in the inner wall of the chambers. These openings are a small distance from the floor of the oven, and run horizontally back one half of the length of the oven. There are no openings in the other wall of the flue or space, L, immediately opposite those described, but each chamber has openings extending half way from the opposite front, so that where the openings on one side of the flue cease, they commence on the other side and extend along to the other front. See Fig. 9.

60 There are two furnaces at opposite corners of the oven, one for each chamber. The construction of one of the furnaces, N, and the flue holes in the front half of one of the chambers is shown in Fig. 8, by representing part of the arched roof and side re-

moved. The railroad tracks A A are laid on the bottom of the oven to receive the trucks T with the glass. The ends of the oven are closed by gates, H, H, suspended on balance beams O', O², O³, O', and counterpoised by weights, W, or by the center gates, R, R, as seen in Fig. 8.

The inner wall S' of the furnace, N, (which is similar in construction to the other furnace at the opposite corner of the oven,) are carried up perpendicularly to a height a little above the level of the floor of the compartments, 4, and, 2, and then turns (see Fig. 10) horizontally at right angles so as to extend about half way over the furnace thus forming a partial covering to it, marked, X. The flame and smoke from the furnace pass around this horizontal covering, X, and as they have no other outlet than the flue holes, Q, Q, etc., they pass down over the glass lying on the trucks, which are on the railway tracks, A, A, and out through these flue holes into the space L, and thence up the chimney, M. The center gates, A, R, divide each chamber into two compartments, of equal size. These compartments I number for the sake of convenience 1, 2, 3, 4. It must be remembered that the construction of compartments Nos. 2, and 4, is similar, they both having furnaces and the flue holes in their inner walls, while compartments Nos. 1, and 3, are also alike and have no furnaces and no flue holes connecting them with the space, L.

When the glass is rolled and placed on the trucks, they are pushed into compartment No. 1; the gate, H, is then lowered, which raises the center gate, R, thus connecting the two compartments together. Compartment No. 1, is not heated by the direct action of the fire, but being heated from No. 2, is of more moderate temperature. The glass remains in No. 1, until warm enough to stand a greater degree of heat, and then the truck is pushed into No. 2, by a pole passed through the hole in the gate, H. Here the heat is more intense, and the flame passes immediately over the surface of the glass, communicating a fire polish. When sufficiently polished, the balance beam, O², is raised, which throws up the gate of compartment, No. 2, and the truck is passed into the open air. Here it stands till the glass is cool enough to be turned, which operation is performed with a fork (shown in Fig. 7,) which catches the sheet of glass by its edges. The lower side being then turned up, the truck is removed to the tracks which lead to compartment No. 3, which corresponds with No. 1, and therefore need not be more particularly described. It enters here and after being warmed up, it passes to compartment No. 4, where it is fire polished. The glass having thus received a fire polish, on both sides, is ready

to be annealed, which process is performed in leers of the ordinary construction.

Having thus described my improved mode of making window or plate glass by machinery, what I claim as my invention and desire to secure by Letters Patent, is—

1. The use of hollow chilled iron rollers in the manufacture of window and plate glass in connection with the mode of heating them with charcoal or other combustible placed inside.

2. The combination of the grooves *o*, *o'* with the strips and guides *i*, *i* and the set

screws *s* for the purpose of regulating the width and thickness of the sheet of glass. 15

3. The use of trucks for carrying off the sheets of glass as they pass from the rollers as aforesaid.

4. The combination and arrangement hereinbefore described of the gates, flues, 20 and furnace in the construction of the polishing oven.

TER. CLARK.
